UNITED STATES PATENT OFFICE.

JOHN C. ENTRIKEN AND WILLIAM S. EVERETT, OF MALVERN, PENNSYLVANIA, ASSIGNORS OF ONE-FOURTH TO SHELDON M. CUSTER, OF WAYNE, PENNSYLVANIA.

LEAD-IN WIRE FOR ELECTRIC LAMPS.

SPECIFICATION forming part of Letters Patent No. 740,260, dated September 29, 1903.

Application filed August 21, 1903. Serial No. 170,358. (No model.)

To all whom it may concern:

Be it known that we, JOHN C. ENTRIKEN and WILLIAM S. EVERETT, citizens of the United States, and residents of Malvern, county of Chester, State of Pennsylvania, have invented certain new and useful Improvements in Lead-In Wires for Electric Lamps, of which the following is a specification.

Our invention relates to electric lamps, such as incandescent electric lights, and more especially to certain improvements in connection with the lead-in wires of the lamp.

The object of our invention is to provide an efficient and economical means of attaching a platinum or other coated lead-in wire to the stem of such a lamp, so designed as to effectually prevent any leakage of air into the bulb after the vacuum has been established.

Attempts have been made to utilize platinum-coated lead-in wires in incandescent electric lamps because of the material reduction in cost which would result from the use of a platinum-coated wire instead of the solid platinum wire now universally employed; but such attempts have proved failures by reason of the fact that it has not been possible prior to our invention to prevent leakage of air from the stem by the embedded lead-in wires into the bulb, thereby destroying the vacuum. It has been commonly supposed that this leakage occurred between the outer surface of the coated wire and the mass of glass of the stem in which the said wire has been embedded; but we have discovered that this leakage occurred between the metallic core and the platinum coating. By our invention we are enabled to prevent the said leakage, and thereby to successfully apply a coated lead-in wire to electric lamps.

Our invention consists, broadly, in the employment, in connection with an electric lamp, of a coated lead-in wire having the end otherwise exposed to the air or to which air had access sealed against such access of air between the coating and the core of the wire, and, further, in such a coated lead-in wire having such end glass sealed against access of air, and, further, in such a coated lead-in wire having such end bent and embedded in

the glass of the stem, whereby it is sealed against access of air and furnishes a ready means of connection with the conducting-wire, and, finally, in the novel construction and details thereof, as hereinafter described with reference to the accompanying drawings, and more particularly pointed out in the claims.

In the accompanying drawings, Figure 1 is a side elevation of an ordinary electric lamp, showing our invention applied thereto. Fig. 2 is an enlarged sectional detail showing the preferred form of sealing the end of the coated lead-in wire. Fig. 3 is a detail view of a modification, and Fig. 4 is a similar view of a further modification.

Referring to the drawings, in which the same reference characters relate to the same parts in all the views, 1 represents an electric-lamp bulb provided with the usual base 2, from which extends the usual glass stem 3, through which stem extend conductor-wires 4, having their ends embedded in the flattened end portion 5 of the tubular stem and in conducting contact with the lead-in wires 6, to which the filament 7 is attached in the usual manner.

According to our invention the lead-in wires 6 are preferably composed of an inner core 8 of a metallic conducting-wire of higher conducting power than platinum—such, for example, as iron, coated with a thin coating 9, preferably of platinum—a conducting contact between said lead-in wires and the conducting-wires 4 being effected by bending the ends of said conducting-wires around the lead-in wires and forcing the same into permanent contact during the operation of closing the lower end of the stem 3 by subjecting the same to pressure, as is well understood by those skilled in the art, or this contact may be secured in any other convenient way. In order to prevent access of air from the stem to the bulb around or through the coated lead-in wire, we seal the end 10, which would otherwise be exposed to the air or to which air might otherwise gain access, preferably by bending the same in such manner that when the lower end 5 of the stem is closed the end 10 will be permanently embedded in

the mass of glass, and thus sealed against access of air, so that it will be impossible for air to penetrate between the core 8 and the coating 9 of said lead-in wire. Thus the passage of air into the bulb is prevented and the vacuum maintained intact. In this form of the invention the bent ends afford a simple means of connecting the conducting-wires, the union between the two being effected in the closing of the end of the stem, thus in closing the joint in the mass of pressed glass.

While the preferable form of our invention is that embodied in Figs. 1 and 2 of the drawings, the same result may be accomplished in a variety of ways, the only requirement being that the end of the coated wire which would otherwise be exposed to the air shall be protected against the access of air. For example, in Fig. 3 we have shown a form in which the end 10^a of the lead-in wire is extended through the flattened or closed end 5 of the stem, so that it will be exposed to the vacuum in the bulb 1 and not to the air, or, if desired, the end 10^b of the lead-in wire 6 may be extended upwardly through the closed end of the stem into the said stem and provided with a seal 11, preferably of glass, so as to effectually close the end of the coated lead-wire against access of air.

30 By the use of our invention a large saving of platinum (the metal possessing the properties most suitable for lead-in wires in electric lights for reasons well known to the art) is effected, for only a very thin coating of platinum is necessary to answer the purpose of the present solid platinum wire.

While our invention is especially adapted to incandescent electric lights, it is to be observed that its utility is not limited in this respect, since it is apparent that it may be applied wherever a coated lead-in wire is used for conveying an electric current into a lamp body or bulb wherein a vacuum must be

45 maintained, and when the term "stem" is employed in this specification it is intended to include the portion of the device through which the lead-in wires pass to the vacuum-bulb, no matter what form that stem may be.

We claim as our invention—

1. In an electric lamp, a coated lead-in wire 50 having its end sealed to prevent access of air between the coating and core of said wire, substantially as described.

2. In an electric lamp, a coated lead-in wire having its end glass-sealed to prevent access 55 of air between the coating and core of said wire, substantially as described.

3. In an electric lamp, a coated lead-in wire having a bent end sealed against access of air between the coating and the core of said wire, 60 substantially as described.

4. In an electric lamp, a coated lead-in wire having a bent end embedded in the glass of the stem, thereby preventing access of air between the coating and core of said wire, 65 substantially as described.

5. In an electric lamp, a platinum-coated lead-in wire having its end protected against access of air between the platinum coating and the core of said wire, substantially as de- 70 scribed.

6. In an incandescent electric lamp, a platinum-coated lead-in wire having its end bent to furnish contact for the conductor-wire, and embedded in and inclosed by the glass of the 75 stem, whereby leakage of air into the bulb through said wire is prevented, substantially as described.

In testimony whereof we have signed our names to this specification in the presence of 80 two subscribing witnesses.

JOHN C. ENTRIKEN.

WILLIAM S. EVERETT.
